UNITED STATES PATENT OFFICE.

ALBERT PERKINS, OF CHICOPEE, MASSACHUSETTS.

DESIGN FOR A CAGE FOR BALL-BEARINGS.

SPECIFICATION forming part of Design No. 28,869, dated June 14, 1898.

Application filed May 10, 1898. Serial No. 680,324. Term of patent 7 years.

To all whom it may concern:

Be it known that I, ALBERT PERKINS, of Chicopee, in the county of Hampden and State of Massachusetts, have invented and produced 5 a new and original Design for Cages for Ball-Bearings, of which the following is a specification, reference being had to the accompanying drawings, forming a part thereof.

Figure 1 shows one of the broader sides of 10 a cage embodying my novel design. Fig. 2 is a view of the cage, looking in the direction of the arrow of Fig. 1. Fig. 3 is a section on the line 3 3, Fig. 1.

As shown in the drawings, the cage consists

of a shallow annular trough having its bottom A provided with large regularly-spaced perforations B and having its walls C C' bent inward near their upper free margins D, and this general form is characteristic of my design. 15

Having now described my new and original design, what I claim is— 20

The design for a cage for ball-bearings, substantially as shown and described.

ALBERT PERKINS.
